A. SCHEUCHZER

RAILROAD TRACK WEEDING MACHINE

Filed May 5, 1924

UNITED STATES PATENT OFFICE.

AUGUSTE SCHEUCHZER, OF RENENS, NEAR LAUSANNE, SWITZERLAND, ASSIGNOR TO FERRODESHERBEUSE SCHEUCHZER SOCIETE ANONYME, OF RENENS, SWITZERLAND.

RAILROAD-TRACK-WEEDING MACHINE.

Application filed May 5, 1924. Serial No. 711,300.

To all whom it may concern:

Be it known that I, AUGUSTE SCHEUCHZER, citizen of Switzerland, residing at Renens, near Lausanne, Switzerland, have invented 5 certain new and useful Improvements in Railroad-Track-Weeding Machines, of which the following is a specification.

The present invention relates to improvements in railroad track weeding-machines 10 and specially to improvements in the arrangement of the test roller which is dragged through the ballast and is adapted to control the steam admission of a servo motor working the weeding knives.

15 There are already such machines where a servo motor is controlled by an arm carrying a test roller which when meeting with an obstacle in the ballast oscillates and acts thereby on the servo motor. But in order 20 to render such oscillation possible it was necessary to maintain said arm resiliently within the ballast. As this ballast however is of a very varying resistance amounting sometimes to a considerable value very 25 heavy springs and mountings of such springs had to be employed which springs and mountings were subjected to much breaking and deformation.

The object of this invention is to get rid 30 of such springs. To this effect a compressed air cushion has been provided for within an auxiliary pneumatic cylinder which cushion acts on the piston which is in operative connection with the test roller. By means 35 of a simple cock it is possible to vary the pressure within the pneumatic cylinder and to adapt according to circumstances the power which maintains the test roller within the ballast. The combination of this 40 pneumatic cylinder with the test roller allows also the pneumatic withdrawal of the roller and of its supporting parts, in order to reestablish the position of rest of all parts.

45 The annexed drawing represents one working form of the object of the invention as an example.

Fig. 1 shows all parts in working position;

50 Fig. 2 shows the parts in the position of rest and

Fig. 3 is a longitudinal section through the auxiliary pneumatic cylinder.

55 According to the drawing the test roller *a* is rotably mounted at the end of an arm *b*,

which is slidably mounted within a guide *c* pivotally held at the end of a slide *d* to which by means of a system of levers a vertical swinging movement may be imparted through a hand wheel *e* which is in operative connection with said levers. It is therefore the position of this hand wheel whereon depends the depth to which the test roller *a* will be sunk into the ballast.

The slide *d* is provided with a tread *f* 65 for a cam roller mounted at the other end of the arm *b*. This end of the arm is also engaged in the slot of an arm *g* fixed on a trunnion *h*. Likewise keyed fast to this trunnion is a crank *i*, which is linked to a 70 connecting rod *k* of a piston moving in an auxiliary pneumatic cylinder *l* pivotally mounted on a bracket of the frame. The two sides of this piston can be put into communication by a four-way cock *l*¹ with a 75 compressed air reservoir provided on the machine.

When a certain amount of air is admitted under the piston of the auxiliary cylinder, crank *i* will turn contrarily to a clockwise 80 movement on the geometrical axis of the trunnion *h*. Arm *g* follows this movement and presses the cam roller at the upper end of arm *b* against the tread *f* in the position of parts, as shown in Fig. 1.

When ever roller *a* meets with a sleeper the members *g*, *h*, *i*, *k* will be operated in a clockwise sense and the air cushion under the piston will be compressed. The initial pressure of said cushion may be adapted according to circumstances, so as to keep the roller *a* sunk within the ballast whatever 90 may be the resistance presented by this ballast to the test roller.

If the apparatus has to be brought at rest 95 and if the roller *a* must be withdrawn from the ballast an air pressure is created on the other side of the piston after having closed the exhaust of this side and opened the exhaust of the opposite side.

100 The members *g*, *h*, *i*, *k* will then move again and swing arm *b* contrarily to a clockwise movement. The upper roller of this arm will follow the tread *f* and bring arm *b* into a position which is about parallel 105 with the rails which position is shown in Fig. 2.

The movement of this last roller controls likewise the admission device of the steam of the working cylinder and reverses this 110

steam so as to cause the withdrawal of the knives from the ballast.

Having now fully described the nature of my invention and the manner in which 5 the same is to be performed, what I claim as new and want to secure by Letters Patent is:

1. In a railroad track weeding machine having knives operated by a servo motor 10 which is controlled by a test roller dragged through the ballast and in combination, an auxiliary pneumatic cylinder, a compressed air cushion formed underneath the piston of said cylinder and mechanical means adapted 15 to establish the working connection between the test roller and said piston so as to maintain said roller resiliently in the ballast.

2. In a railroad track weeding machine having knives operated by a servo motor 20 controlled by a test roller which is dragged through the ballast and in combination, an auxiliary pneumatic cylinder; means for

creating a compressed air cushion on the one side of said piston; means for establishing the working connection between said piston and said roller and means adapted to render either side of the cylinder suitable as exhaust or working side. 25

3. In a railroad track weeding machine having knives operated by a servo motor 30 controlled by a test roller, in combination a compressed air reservoir; an auxiliary pneumatic cylinder set in communication with said reservoir, means for establishing the working connection between the piston of said cylinder and said roller and a four-way cock adapted to control the communication between cylinder and reservoir so as to render either side of the cylinder suitable 35 as working or as exhaust side. 40

In testimony whereof I affix my signature.

AUGUSTE SCHEUCHZER.
